United States Patent

Des. 241,696
Patented Oct. 5, 1976

241,696

FILE CART

Frank Joseph Stiene, Ridgewood, N.J., assignor to
Mercedes-Benz of North America, Inc.

Continuation of design applications Ser. Nos. 282,584,
and 282,585, Aug. 21, 1972, both now abandoned. This
application Nov. 5, 1974, Ser. No. 521,140

Term of patent 14 years

Int. Cl. D6—04

U.S. Cl. D6—186

FIG. 1

FIG. 2

FIG. 3

FIG.4

FIG.5

FIG.6

FIG. 7

FIG. 8

FIG. 9

FIG. 11**FIG. 12**FIG. 1 is an oblique perspective view from in front and above, of a file cart embodying my novel design;

FIG. 2 is a side view from one side of the file cart of FIG. 1;

FIG. 3 is a side view from the other side of the file cart of FIG. 1;

FIG. 4 is an end view of the file cart of FIG. 1;

FIG. 5 is a bottom view of the file cart of FIG. 1;

FIG. 6 is a top view of the file cart of FIG. 1;

FIG. 7 is an oblique perspective view from in front and above, of a file cart embodying another embodiment of my novel design;

FIG. 8 is an end view of the file cart of FIG. 7;

FIG. 9 is a side view of the file cart of FIG. 7;

FIG. 10 is a side view of the file cart of FIG. 7 of the side opposite the view taken in FIG. 8;

FIG. 11 is a bottom view of the file cart of FIG. 7; and

FIG. 12 is a top view of the file cart of FIG. 7.

This application is a continuation of my prior U.S. applications, Ser. Nos. 282,584 and 282,585, both filed Aug. 21, 1972 and now abandoned.

I claim:

The ornamental design for file cart, as shown and described.
